US0D1031732S

(12) **United States Design Patent** (10) **Patent No.:** **US D1,031,732 S**
(45) **Date of Patent:** **** Jun. 18, 2024**

(54) **STYLUS PEN**

Primary Examiner — Austin Murphy

(71) Applicant: **Changsha Juhexing Import and Export Trading Co., Ltd.**, Hunan Province (CN)

(57)

CLAIM

(72) Inventor: **Yan Yang**, Hunan Province (CN)

The ornamental design for a stylus pen, as shown and described.

(**) Term: **15 Years**

(21) Appl. No.: **29/870,158**

DESCRIPTION

(22) Filed: **Jan. 18, 2023**

(30) **Foreign Application Priority Data**

Dec. 13, 2022 (CN) 202230835351.X

FIG. 1 is a front and top perspective view of a stylus pen, showing my new design;

(51) **LOC (14) Cl.** **14-02**

FIG. 2 is a rear and bottom perspective view thereof;

(52) **U.S. Cl.**

FIG. 3 is a front elevation view thereof;

USPC **D14/411**

FIG. 4 is a rear elevation view thereof;

(58) **Field of Classification Search**

FIG. 5 is a left side elevation view thereof;

USPC D14/372, 496, 432, 371, 125, 126, 129,
D14/299, 411; D16/300–342; 351/158,
351/153, 144; 345/7–9, 905; 455/344;
348/115, 53, 121, 739

FIG. 6 is a right side elevation view thereof;

CPC G02B 27/017; G06F 3/016; G06F 3/033;
G06F 3/0317; G06F 3/03545; G06F
3/041; G06K 9/222

FIG. 7 is a top plan view thereof;

See application file for complete search history.

FIG. 8 is a bottom plan view thereof;

(56) **References Cited**

FIG. 9 is a perspective view thereof, shown with an additional stylus pen in a disassembled configuration;

U.S. PATENT DOCUMENTS

FIG. 10 is another perspective view thereof, shown in an assembled configuration;

FIG. 11 is another perspective view thereof, shown with two additional stylus pens in a disassembled configuration;

(Continued)

FIG. 12 is another perspective view thereof, shown in an assembled configuration;

FIG. 13 is another perspective view thereof, shown with three additional stylus pens in a disassembled configuration;

FIG. 14 is another perspective view thereof, shown in an assembled configuration;

FIG. 15 is another perspective view thereof, shown with four additional stylus pens in a disassembled configuration; and,

FIG. 16 is another perspective view thereof, shown in an assembled configuration.

The broken lines are shown for the purpose of illustrating both parts of the stylus pen as well as environmental subject matter. None of the broken lines form part of the claimed design.
